UNITED STATES PATENT OFFICE.

JOHN W. VAN DYKE, OF BROOKLYN, NEW YORK.

STEAM-BOILER.

SPECIFICATION forming part of Letters Patent No. 289,322, dated November 27, 1883.

Application filed April 4, 1883. (No model.)

To all whom it may concern:

Be it known that I, JOHN W. VAN DYKE, of Brooklyn, in the county of Kings and State of New York, have invented certain Improvements in Steam-Boilers, of which the following is a specification.

This invention relates to that class of steam-boilers commonly termed "water-tube boilers;" and its object is to provide a simple, strong, and efficient boiler in which provision shall be made for the most advantageous circulation of the water and the free and unimpeded disengagement of the steam from the boiler, and in which the injury to the structure of the boiler incident to expansion and contraction arising from changes of temperature shall be reduced to the lowest possible degree.

The invention comprises certain novel combinations of parts whereby these objects and results are secured.

Figures 1, 2, and 3 are vertical transverse sectional views, representing various features and modifications of my said invention, and taken in a vertical plane corresponding to that indicated by the dotted lines *x* in Fig. 4. Fig. 4 is a longitudinal vertical sectional view, illustrating my said invention; Fig. 5 is a front elevation of my improved boiler, and Fig. 6 is a horizontal section thereof on line *y y* of Fig. 4.

Having reference first to Fig. 1, *A* are headers designed to connect the tubes of the boiler, as hereinafter explained, and rectangular in their cross-section, with flat sides, and intended to be placed on end—that is to say, vertical—to constitute the ends of the boiler. They are intended to be made of cast-iron or cast-steel, and each is divided horizontally by the partitions *a* into chambers *A'*. Each of these headers is provided at its inner side with a pair of openings communicating with each of the chambers *A'*, said openings being of such size and shape as to receive the adjacent inserted ends of the tubes *B*, which are preferably secured therein by being expanded into the said openings. The outer side of each of said headers is provided either with hand-holes arranged one opposite each of the openings *B'*, or, in lieu thereof, the said headers may be originally formed with said outer side opened, and when put into use and operation have said sides closed by large plates *B''*, each cor-

responding to the size and contour of the chamber *A'* over or upon which it is placed, the said plates being held in position by suitable bolts, *d*. The tubes *B* are arranged in series, zigzagged vertically, as represented in Fig. 4, in such manner that the water from the lowermost of the chambers *A'* at the front of the boiler may pass back and forth through the several chambers of the headers at the opposite end of the boiler until it reaches the uppermost of said headers, and passes thence into a steam-discharging chamber, *C*, placed at the top of said headers at the rear of the boiler, the said steam-discharging chamber communicating by a passage, *C'*, with the steam-drum *D*, which latter has adjacent to the passage *C'* a vertical partition, *c*, which extends up from the bottom of the drum to or above the middle thereof, the object being to prevent the downward flow of the water from the rear of the said drum, if in any case the normal circulation of the water through the boiler should be checked or reversed.

The front of the steam-drum *D* communicates with the lowermost of the chambers *A'* of the headers *A* by means of a chamber, *E*, in direct communication with said end of said drum and tubes *F*, which communicate with a base-chamber, *G*, with which the lowermost ends of the tubes communicate, as shown at *e* in Fig. 4. The tubes *F* communicate with the base-chamber *G* at the ends of the latter—as, for example, at the parts indicated at *f* in Fig. 5—the said ends of the base-chamber being bolted direct to the tubes *F*, so as to be suspended thereby, the said tubes *F* being extended farther down, resting upon suitable foundations, and the other lower parts constituting mud-drums for the boiler.

The fire-box *H* may be arranged in any suitable or usual relation to the tubes of the boiler, and the latter may be provided at its sides with the usual brick-work, *I*.

In the operation of the boiler the water from the lowermost of the tubes circulates from one to another of each of the vertical zigzagged series through the headers of such series, thence through the chamber *C* into the drum *D*, and, after traversing the latter, into the base-chamber *G*, and thence again into the lowermost of the tubes, the steam being readily disengaged from the water, as the latter passes up the

chamber C behind the partition c into the drum. As represented in Fig. 1, and hereinbefore set forth, the headers are shown and described in their simpler form.

5 Further features of my said invention comprise additional construction and operation of the said headers in their relation to the tubes.

Having reference now to Fig. 2, in connection with Figs. 4, 5, and 6, the headers are made double—that is to say, are not only horizontally divided into the chambers A', but are divided by vertical partitions m, so that each header comprises two parallel vertical series 15 of chambers, A', formed in one and the same casting. In this case one of the narrow headers hereinbefore described is employed at each end of the boiler and at opposite sides thereof, as illustrated in plan view Fig. 6, so that 20 while any two adjacent tubes in the same inclined plane shall at one end enter one and the same header, at their opposite ends they shall enter separate headers, the said tubes of each horizontal plane therefore, taken in connection with their headers, forming zigzagged 25 water-courses, as illustrated in said Fig. 6. When the vertical partitions of these last-mentioned headers extend from top to bottom of the chambers A', the operation of the boiler 30 will be substantially the same as that when the ends of the said boilers are made up of the narrow headers shown in Fig. 1, and hereinbefore fully described; but by forming openings in the said vertical partitions at or near the 35 upper ends of each of the chambers A', a lateral circulation of the water from one of the vertical series of tubes to the other may be suffered to take place, to this extent modifying in some degree the circulation of the water.

40 Having reference to Fig. 3, taken in connection with Figs. 4, 5, and 6, the vertical partition m is replaced by two internal parallel walls, n, having spaces r between them, and with the opening p in both of them at or near 45 the top of the chamber A', and with, furthermore, openings at the bottom through the said walls, and also an opening through the horizontal partitions a coincident with the said walls, as represented at r', this construction 50 and arrangement facilitating the disengagement of steam from the upper part of the chambers A'—in other words, to prevent the locking of superheated steam in the cavities above the ends of the tubes B.

55 It will be observed that the arrangement of the headers and the holes and partitions therein leaves the tubes in straight lines, whether viewed horizontally or vertically. The horizontal arrangement leaves a clear horizontal 60 space between any two series of tubes, which admits of the passage of cleaning devices between said tubes, and also of the use of the tiles T shown in Fig. 4.

What I claim as my invention is—

65 1. The compound vertical headers horizontally divided into chambers, as set forth, and

constructed with internal vertical walls, in combination with the tubes B, arranged to form zigzag series vertically and horizontally, leaving a clear horizontal passage between 70 each series, as described, said headers being placed side by side to form the ends of the boiler, all substantially as and for the purpose herein set forth.

2. The compound vertical headers horizontally divided into chambers and provided with internal vertical parallel walls, n, having a space, r, between them, and openings p in said walls at or near the top of each chamber, in combination with the tubes B, arranged to 80 form zigzag series vertically and horizontally, substantially as and for the purpose herein set forth.

3. The combination of the narrow vertical compound headers, the compound headers internally divided into series of parallel vertical compartments, and the tubes B, arranged in zigzag series vertically and horizontally, all substantially as and for the purpose herein set forth.

4. The combination of the narrow vertical compound headers, the compound headers internally divided by parallel vertical walls n, having space r between them, and provided with openings p, and the tubes B, arranged in 95 zigzag series vertically and horizontally, all substantially as and for the purpose herein set forth.

5. The combination of compound headers divided into chambers by horizontal partitions, and placed side by side to form the ends of the boiler, the tubes B, arranged in vertical zigzag series, the steam-discharging chamber C, formed independently of the vertical headers and receiving one series of tubes, and the 105 drum D, all substantially as and for the purpose herein set forth.

6. The combination of compound headers divided into chambers by horizontal partitions, and placed side by side to form the ends of the boiler, the tubes B, arranged in vertical zigzag series, the steam-discharging chamber C, formed independently of the vertical headers and receiving one series of tubes, the drum D, and the return-pipes, all substantially as 110 and for the purpose herein set forth.

7. The combination of compound headers divided into chambers by horizontal partitions, and placed side by side to form the ends of the boiler, the tubes B, arranged in vertical 115 zigzag series, the steam-discharging chamber C, formed independently of the vertical headers and receiving one series of tubes, the drum D, the return-pipes F, and partition placed in said drum adjacent to the steam-discharging 120 chamber, all substantially as and for the purpose herein set forth.

JOHN W. VAN DYKE.
